UNITED STATES PATENT OFFICE.

LEO J. SCHUMACKER, OF DAYTON, OHIO.

HAIR CURLER.

Application filed June 29, 1927. Serial No. 202,230.

This invention relates to new and useful improvements in hair curlers.

It is the principal object of my invention to provide for the curling of hair, and more particularly, in permanent waving, an instrument upon which the hair is wound, and then twisted without the use of a wrench or by pulling out the turning member.

My hair curler may be easily manipulated without discomfort to the one whose hair is being curled, requiring neither a pull upon the instrument nor the removal of one hand therefrom to use a wrench in its operation. Containing few parts, it also may be economically manufactured.

In the accompanying drawings, Figure 1 is a side view of my improved hair curler. Figure 2 is a longitudinal, sectional view taken through the same. Figure 3 is a cross sectional view taken on the line 3-3 of Figure 2. Figure 4 is a cross sectional view taken on the line 4-4 of Figure 2, showing the roller stop for the nut, to prevent the twisting member from turning in a reverse direction. And Figure 5 is a cross sectional view taken through the bifurcated end of the twisting member on the line 5-5 of Figure 2.

Referring to the accompanying drawings for a detailed description of my invention, the numeral 1 designates a sleeve of gradually diminishing diameter from its rear to its front portion. Rotatable in the front end of said sleeve 1 is the reduced end 2 of a bifurcated string receiving member 3.

Screwed into the reduced portion of the bifurcated member 3 is the threaded end of a rod 4 which terminates beyond the outer end of the sleeve in a flat portion 5. The latter is rotatable in a countersunk part 6 of a knurled head 7 having a reduced lower end which is fixedly secured by a pin 8 in the upper countersunk end of the sleeve 1.

The head 7 is formed in its outer end with a wide circular recess 9 to receive a stop or brake member 10 formed with a right-angled notch 11 in its periphery. Within the notch portion of this stop member 10 which is preferably of disc shape, is a rolling pin 12 which is free to be carried clockwise around the interior of the head 7 by the stop member, but will wedge against the latter to prevent its being turned in a reverse or counter-clockwise direction.

This stop member 10 has an oblong cen-

tral hole to receive the flat part 5 of the rod 4 to prevent the latter from being turned in a counter-clockwise direction. For the purpose of turning it in a clockwise direction I have provided a knurled nut 13 which has a reduced projecting end 14 for entrance into the head 7 for a free turning movement therein. The nut 13 has a bottom which is formed with an oblong hole to receive the flat part 5 of the rod 4 to rotate the latter.

The rod 4 terminates at its outer end in a threaded portion 15 to receive a retaining screw 16 that closes the outer end of the nut 13. Surrounding the rod between the bottom of the nut 13 and the screw 16 is a helical spring 17 against the tension of which the screw is adapted to draw the rod 4 to adjust the engagement between the bifurcated member 3 and the anterior end of the sleeve 1.

When a strand of hair is secured to the bifurcated member 3 and wound around the sleeve 1, the strand may be easily twisted or wound to the desired tautness by turning the nut 13 clockwise, the stop member 10 preventing a reverse movement of the rod 4 to hold the strand of hair at the desired degree of security. With my device, no pulling movement or wrench is necessary to accomplish results.

I do not wish to be limited to the details of construction and arrangement herein shown and described, and any changes or modifications may be made therein within the scope of the subjoined claims.

Having described my invention, I claim:

1. An instrument for curling hair, comprising a sleeve, a rod rotatable in said sleeve, a hair securing element on one end of said rod beyond the sleeve, a turning member on the other end of the rod beyond the sleeve, a hollow cylindrical head for the sleeve between it and the turning member, and a stop member secured to said rod within said head for the purpose specified.

2. An instrument for curling hair, comprising a sleeve, a rod rotatable in said sleeve, a hair securing element on one end of said rod beyond the sleeve, a turning member on the other end of the rod beyond the sleeve, a hollow cylindrical head for the sleeve between it and the turning member, and a rolling pin stop member secured to said rod within said head for the purpose specified.

3. An instrument for curling hair, comprising a sleeve, a rod rotatable in said sleeve, a bifurcated hair securing element on one end of said rod beyond the sleeve, a turning nut on the other end of the rod beyond the sleeve, a hollow head on said sleeve, into which said nut projects, and a rolling pin stop member surrounding said rod within the hollow head for the purpose specified. 5. An instrument for curling hair comprising a sleeve, a rod rotatable in said sleeve, a hair securing element on one end of said rod for engagement with its respective end of the sleeve, a hollow head secured to the other end of the sleeve, a nut secured to said rod beyond the head for rotating it in one direction, means secured to said rod within the head for preventing its rotation in the reverse direction, said rod having a threaded portion projecting into said nut, a screw secured to the threaded end of said rod, and a spring surrounding said rod between said screw and the bottom of the nut. 25 30 35
- 10 4. An instrument for curling hair, comprising a sleeve, a rod rotatable in said sleeve, a bifurcated hair securing element on one end of said rod beyond the sleeve, a flattened portion on the other end of said rod, a turning nut secured to the flattened portion of said rod, a hollow head secured to said sleeve and containing the flattened portion of said rod, a stop disc secured to the flattened portion of the rod within said 20 head, and formed with a right-angled notch
- In testimony whereof I have hereunto set my hand this 25 day of June, 1927.

LEO J. SCHUMACKER.
